UNITED STATES PATENT OFFICE.

CHARLES F. LOCKHART AND EVERETT H. ROBY, OF CLEVELAND, OHIO.

WASHING MACHINE.

1,418,586.

Specification of Letters Patent. Patented June 6, 1922.

Application filed June 14, 1921. Serial No. 477,484.

To all whom it may concern:

Be it known that we, CHARLES F. LOCKHART and EVERETT H. ROBY, citizens of the United States, residing at Cleveland, in the 5 county of Cuyahoga and State of Ohio, have invented certain new and useful Improvements in Washing Machines, of which the following is a specification.

This invention relates to washing machines the principal object of which is the cleansing of clothes by suction, vacuum, and hydraulic action combined instead of the usual method of pounding.

A further object of the invention is to provide a machine wherein the clothes being washed in said machine have an everchanging surface or body of clothes passing through the suction process, thereby eliminating waste time as in other types in which 20 the same surface of material is washed again and again.

A further object of the invention relates to the non-clothes wearing quality of the machine wherein owing to the peculiar action of the machine, the operation does not require as much time as formerly, thereby saving considerable in wear and tear on both clothes and machine.

Another object of the invention is to provide a machine which has no exposed working parts such as gears, etc. when in operation, thereby eliminating all possible chance of the operator getting hurt in any way.

Another object of the invention is to provide a machine wherein such elements are introduced in all working parts and in such a manner that the machine does not require any oiling whatever, thereby eliminating many of the present troubles of the housewife.

Another object of the invention is to provide a washing machine wherein all moving parts and mechanical parts are so placed and distributed that none of them comes in contact with either steam or water, thereby increasing the efficiency and life of the machine in general as no oxidation can take place.

Another object of this invention is to provide a washing machine that is so constructed that the clothes being washed in same will not get torn through any mechanical action of the parts.

Another object of the invention is to provide a washing machine constructed in its interior of material which will not suffer

gradual decomposition through the action of washing chemicals introduced for bleaching clothes.

A further object of the invention is to provide a washing machine which, when in operation, is practically noiseless, and one in which energy transmitted is so balanced that vibration is practically nil.

Another object of the invention is to provide a washing machine in which the operating levers are so positioned that they are readily accessible from any position.

Another object of the invention is to provide a machine of this character which is 70 simple and durable in construction, reliable and efficient in operation, and one which can be placed upon the market at a minimum cost.

The invention also consists of certain other 75 features of construction and in the combination and arrangement of the various parts to be hereinafter fully described and illustrated in the accompanying drawings and specifically pointed out in the appended 80 claims.

Describing our invention in detail, reference will be had to the accompanying drawing wherein like characters designate corresponding parts throughout the several views 85 and in which Fig. 1 is a vertical sectional view of the entire machine; Fig. 2 is a side elevation looking from the right of Fig. 1, parts being in section; Fig. 3 is a top plan view of the machine, the cover and wringer 90 being removed; Fig. 4 is a horizontal section on the line 4—4 of Fig. 1; Fig. 5 is a detail sectional view of the wringer; Fig. 6 is a detail sectional view showing the manner of connecting the cup header plate to the 95 cross bar; Fig. 7 is a sectional view showing gearing and clutches for operating the wringer; Fig. 8 is a vertical sectional view of one of the suction cups; Fig. 9 is a section on the line 9—9 of Fig. 8; Fig. 10 is a 100 vertical section through another type of suction cup; Fig. 11 is a section on the line 11—11 of Fig. 10.

Referring to the drawings; 1 is a tub forming the outside or containing element 105 which is fastened to a plate casting 2 supported by legs 3 which are braced and reinforced by a lower plate 4 upon which is assembled the driving mechanism. It will be noted that the lower plate is so constructed 110 that all working parts are housed between the plates 2 and 4.

An electric motor 5 mounted on the plate 4 drives, through a belt 6, a large pulley 7 which is keyed to a shaft 8 mounted in bearings 9 and 10 which are of the self-lubricating type.

Loosely mounted on the shaft 8 is the female member 11 of a cone clutch which carries a small gear 12 which meshes with a large gear 13 keyed to a shaft 14 which is mounted in bearings 15 projecting upwardly from the plate 4. The male member 16 of the cone clutch is slidably keyed to the shaft 8 and is moved into and out of engagement with the female member 11 by an operating means, which consists of the horizontal rod 17 journaled in bearings 18 projecting upwardly from the plate 4 and has its outer ends turned upwardly as at 19 to form convenient operating levers on each side of the machine. Springs 20 hold the levers 19 in the position placed. The rod 17 is bent downwardly and across to form a crank 21 which is connected to the hub 22 of the male member 16 by a pin 23.

Mounted on each end of the shaft 14 are cranks 26 which are connected by links 27 to vertical reciprocating rods 28 which work through bearings 29 and tubes 30 projecting upwardly within the tub 1. The upper end of each tube 30 has a self-lubricating bearing 31 and stuffing box 32 which are rigidly connected to the walls of the tub 1 by brackets 33. One rod 28 is bifurcated as at 34 and carries the header cross beam 35 on a pivot pin 36, and the other rod 28 has a gravity latch 37 pivoted at 38 to securely hold the cross beam 35 in position. While the machine is in operation an inner or clothes-containing tub or basket 39 rests on a ring 40, which has central cross pieces 41, and said ring 40 in turn rests on springs 42 which in turn rest on a plate 43 placed on the bottom 44 of the outer tube 1. As will be noted the tub 39 has its side walls perforated as shown at 45 and it is placed within a ring 46 which is attached to the upper end of rods 47 which work in tubes 48 similar to the tubes 30 and having bearings 49 and 50 at their lower and upper ends, respectively and stuffing boxes 51 above the bearings 50.

The lower ends of the rods 47 have the ends of a cable 52 attached thereto as indicated at 53, said cable passing over sheaves 54 and being connected at 55 to a foot lever 56 which is pivoted at 57 to a bracket 58 extending upwardly from the plate 4.

By pressing downwardly on the pedal 56 the rods 47 and ring 46 are raised until the ring 46 comes into contact with lugs 58^a on the tub 39 which in turn raises the inner tub 39. This is done when the cross beam 35 and connected parts have been swung upwardly into a vertical position around the pivot pin 36 and held in this position by

passing a pin through the hole 60 in a bar 61, (which is mounted in a housing 62 and which can be raised in this housing by lifting the knob 63) and the hole 64 in a lug 65 carried by the cross bar 35. This lifting of the tub 39 raises it out of the water in the tub 1 and allows the water in the clothes within the tub 39 to drain out through the perforations 45. The clothes can then be taken from the tub and wrung through the wringer 66, which is carried on the upper end of a tube 67 whose lower end is connected to a housing 68 in which is contained the gearing and clutches for operating the wringer which will now be described.

Rotatably mounted on the shaft 8 within the housing 68 are the female members 69 and 70 of two cone clutches. Rigidly connected to members 69 and 70 are pinions 71 and 72 which mesh with a pinion 73 keyed to a vertical shaft 74 which extends upwardly within the tube 67. The male members 75 and 76 of the clutches are slidably keyed to the shaft 8 as indicated at 77 and 78 and are held in spaced relationship to each other by a yoke 79 which is slidably mounted in brackets 80. The yoke 79 is moved in either direction by a crank which has its horizontal arm 81 pivotally connected to the yoke as indicated at 82 and has its vertical arm 83 extending upwardly from the housing 68 parallel to the tube 67 and has handles 84 and 85 on its upper end extending to either side of the tube 67. As will readily be seen, by operating the handles 84 and 85 and yoke 79, the shaft 74 may be kept at rest or caused to rotate in either direction by engaging the respective clutches.

Attached to the upper end of the tube 67 is a block 86 having notches 87, said block 86 supporting the wringer-carrying bracket 88. An arm 89 shaped as shown, is pivoted at 90 between lugs 91 on the bracket 88 and has its lower end 92 inserted through a hole 93 into one of the notches 87. A spring 94 tends to keep the arm 89 in this position. This arm will lock the wringer in any desired position as there are about 12 notches 87 in the block 86.

Keyed to the upper end of the shaft 74 is a beveled gear 95 which meshes with a gear 96 on a shaft 97 which operates the lower roller 98 of the wringer 66. A gear 99 on the shaft 97 meshes with a gear 100 on the shaft 101 of the upper wringer roll 101.

Rotatably mounted in the header cross beam 35 is an internally threaded bushing 102 into which is screwed a shaft 103 said shaft being locked in the bushing 102 by a lock nut 104.

Rigidly connected to the lower end of the shaft 103 is a cup header plate 105 which carried a series of suction cups 106. The cups 106 have necks 107 which extend

through openings 108 in the header 105 and are held therein by a cap 109 which has openings 110. The necks 107 are bored out as at 111 and have a check valve 112 resting on a 5 seat 113 in the upper end of the neck.

Formed on the upper end of the bushing 102 is a ratchet wheel 114 which has a cover 115 and to which cover is pivotally connected one end of an arm 116 and a pawl 117. A 10 spring 118 has one end connected to the pawl 117 and the other end connected to the arm 116. The other end of the arm 116 is connected to the inner end of a bar 119 which is slidably carried on the upper face of the 15 header cross beam 35 and is slotted as at 120 to allow for the lug 65. The other end of the bar 119 is bent at right angles as at 121 and then downwardly and outwardly as at 122 and carries a roller 123 which is adapted 20 to engage with an inclined lug 124 on the inside of the tub 1 on the up stroke of the rods 28 and the header cross beam 35. A small rod 125 extends rearwardly from the part 25 122 and through a bracket 126 carried on the side of the cross beam 35. A spring 127 is coiled around the rod 125 between the bracket 126 and the part 122.

As the roller 123 engages the inclined lug 124 on the upward stroke of the rods 28 the 30 bar 119 is moved along the header 35 and in turn moves the arm 116 which rotates the cover 115 and consequently the ratchet wheel 114 as the pawl 117 is in engagement within the teeth of the ratchet 114. As the ratchet 35 114 is rotated the bushing 102 will be rotated and consequently the shaft 103, which is rigidly locked in it and the cup header 105 which is rigidly fastened to the lower end of the shaft 103. On the downward stroke of 40 the rods 28 and header 35 the roller 123 will leave the inclined surface 124 and the spring 127 will force the bar 119 in the opposite direction which in turn will bring the pawl 117 back and into engagement with one of 45 the succeeding teeth of the ratchet wheel 114.

As will readily be seen the shaft 103 and cup header 105 and cups 106 carried thereby will be slightly rotated at every upward movement of the rods 28 and header cross 50 beam 35.

The rods 28 will be moved up and down through the action of the cranks 26 and links 27 when the shaft 14 is rotated. 130, 131 and 132 indicate depressions in the plate 4 to 55 receive the cranks 26, wheel 7 and gears 13 and 12. Depressions to receive the lower ends of the rods 47 are indicated at 135.

Figs. 10 and 11 illustrate a different type 60 of cup which may be used in place of the cups 106. This cup consists of a conical member 140 which has a cylindrical neck 141 into which fits a hollow cylinder 142. Fastened to the upper end of the cylindrical neck 141 and extending through slots 143 in 65 the cylinder 142 are two cross bars 144 placed

at right angles to each other. Above the cross bars is a disk 145 upon which is placed the lower end of a spring 146, the upper end being held by a cap 147 which is threaded onto the upper end of the cylinder 142. The 70 cylinder 142 is screwed into openings in the cup header 105 and the cap 147 also acts as a lock nut.

A fibre washer 150 may be placed on the bottom of the cylinder 142, and be held by a 75 screw 151.

In operation, the beam 35, and the suction cups connected thereto, are swung up 80 out of the tub 39, and the clothes are placed in the tub, and the beam and cups swung down to original position. When the machine is started the rotation of the shaft 14, by means of the connecting rods 28, causes an up and down motion of the suction cups, and the tub 39 will yield to a certain extent 85 in consequence of the springs 42. This action has the effect of pumping the water through the clothes, and the clothes are compressed at each operation. As the cups lift suction through the clothes is induced 90 and the cups fill with water which is discharged on the next down stroke and escapes through the openings 45 in the tub 39 and flows downwardly to the bottom of the outer tub and again circulates through the clothes. 95 At each stroke the gang of cups is rotated slightly to apply the same to a new portion of the clothes. The screw 103 permits an adjustment to vary the amount of pressure applied to the clothes, or to accommodate 100 different quantities of clothes. The machine may be run at any speed desired, and it has been found that as high as seventy-five strokes per minute may be successively used, giving a multiplicity of operations which 105 will speedily clean the clothes. After they are cleaned, the whole inner basket or tub may be lifted by pressing on the treadle 56, and the clothes then passed from the basket to the wringer and wrung out in the ordinary way, the wringer being driven by the same power as the washer.

The washing machine proper is claimed in this application, the suction cups and wringer gearing and other features being 110 reserved for separate applications.

We claim:

1. In a washing machine, the combination with an outer tub, an inner perforated tub therein, springs between the bottoms of the 120 inner and outer tubs, suction cups in the inner tub, and means extending in the space between the sides of the inner and outer tubs to reciprocate the suction cups.

2. In a washing machine, the combination 125 with an outer tub, an inner perforated tub therein, springs between the bottoms of the inner and outer tubs, suction cups in the inner tub, means extending in the space between the sides of the inner and outer tubs 130

to reciprocate the suction cups, and means actuated by the reciprocation of the suction cups to revolve the same.

3. In a washing machine, the combination 5 of an outer tub, a spring supported perforated inner tub movable up and down within the outer tub, suction cups movable up and down in the inner tub and adapted by such movement to vibrate the inner tub up and 10 down, means extending in the space between the sides of the inner and outer tubs to operate the suction cups, and means automatically actuated by the up and down movement of the cups to revolve the same step by 15 step.

4. In a washing machine, the combination 20 of an outer tub, a spring supported perforated inner tub movable up and down within the outer tub, suction cups movable up and down in the inner tub and adapted by such movement to vibrate the inner tub up and down, means extending in the space between the sides of the inner and outer tubs to operate the suction cups, and means automatically actuated by the up and down movement of the suction cups to revolve the same step by step, said last mentioned means including a reciprocating rod located above the inner tub and connections between said 30 rod and the cups to revolve the same.

5. In a washing machine, the combination 35 of outer and inner tubs, vertical rods extending through the bottom of the outer tub and connected to the inner tub, and a lever connected to said rods and adapted to lift the inner tub when depressed.

6. In a washing machine, the combination 40 of outer and inner tubs, vertical rods movable up and down through the bottom of the outer tub and in the space between the sides of the tubs, a cross head connected to the upper ends of said rods, suction cups connected to said cross head and working in the inner tub, and means to operate the rods.

- 45 7. The combination with an outer tub and

an inner perforated tub therein, of suction cups in the inner tub, means to work the same up and down, a plurality of rods extending through the bottom of the outer tub and engaging the inner tub, means to raise or lower said rods, to raise or lower the inner tub, and means to automatically revolve the cups, by the operation of the rods when said cups are in raised position.

8. The combination with inner and outer 55 tubs, of a gang of suction cups working up and down in the inner tub, a cross bar to which said cups are connected, reciprocating rods connected to opposite ends of the cross bar and working through the bottom of the 60 outer tub and between the side walls of the inner and outer tubs, a crank shaft located under the bottom of the outer tub and connected to said rods, and means to drive the crank shaft.

65 9. The combination of an outer tub, an inner perforated tub removable up and down therein, a plurality of rods movable up and down through the bottom of the outer tub, a ring carried by the upper ends of said rods and loosely engaging the inner tub to lift the same, and a lever connected to said rods below the bottom of the outer tub, to lift the same.

70 10. The combination with a tub, of a cross 75 bar extending across above the same, a screw adjustable on the cross bar, a gang of suction cups carried by the lower end of the screw, and means to raise and lower the cross bar, and means actuated by the up and down 80 movement of the cross bar to rotate the screw and the cups carried thereby.

In testimony whereof, we do affix our signatures in presence of two witnesses.

CHARLES F. LOCKHART.
EVERETT H. ROBY.
